Primary Examiner — T Chase Nelson

(74) Attorney, Agent, or Firm — Hogan Lovells US LLP

(57) **CLAIM**

The ornamental design for a shoe sole, as shown and described.

DESCRIPTION

FIG. 1 is a front left-side perspective view of a first embodiment of a shoe sole showing my new design; FIG. 2 is a front right-side perspective view thereof; FIG. 3 is a front perspective view thereof; FIG. 4 is a rear perspective view thereof; FIG. 5 is a left-side perspective view thereof; FIG. 6 is a right-side perspective view thereof; FIG. 7 is a top perspective view thereof; FIG. 8 is an exploded rear-side left perspective view thereof; FIG. 9 is a front left-side perspective view of a second embodiment of a shoe sole; FIG. 10 is a front right-side perspective view thereof; FIG. 11 is a front perspective view thereof; FIG. 12 is a rear perspective view thereof; FIG. 13 is a left-side perspective view thereof; FIG. 14 is a right-side perspective view thereof; FIG. 15 is a top perspective view thereof; and, FIG. 16 is an exploded rear-side left perspective view thereof.

FIGS. 1-16 depict a first and second embodiment of a design for a left shoe sole. The third and fourth embodiments are for the right shoe sole with Embodiment 3 being a mirror image of the first embodiment and Embodiment 4 being a mirror image of the second embodiment.

The broken lines appearing in FIGS. 1-16 are to show the environment and form no part of the claimed design.

1 Claim, 16 Drawing Sheets
